C. F. FISHER.

Alcohol Still.

Patented Apr 24, 1830.

NO PRINTED COPY OF SPECIFICATION IN OFFICE.

245.
Charles H. Fisher.

Letters Patent. (Patented April 24th 1830.)
 The Schedule referred to in these Letters Patent forming
 part of the same, containing a description in the words of
 the said Charles H. Fisher himself of his improvement in
 the Art of Distilling.

The manner of using the C. H. Still: To charge the
 double still with a tin or copper pump at (letter D) with
 12 to 14 gallons of jingleings; next, then charge the lower
 still at letter H with the beer, stirring at the hole G, until
 you see that the beer begins to boil, then shut both holes tight
 then the vapors passes thro C the steam pipe to D the separa-
 tor; & in about 17 minutes the still will commence to run
 the liquor (spirit) at the end of the worm, (while the
 liquor is running the fire must be kept even) & the
 door shut at the furnace, until the liquor is off, afterward
 you may run the still faster by giving a little vent or
 more fire, (the stiller will now learn to regulate the
 fire,) when the liquor is run off you leave 12 or 14 gallons
 jingleings run off, which is to be put into the doubling still
 then you let the water out of the small still at the cock
 & you tap off the slop in the lower still: fill it again as
 before & the doubling still with 12 or 14 gallons of sin-
 gling as above stated & I should. any beer from the
 still below get into the still above, you must leave off
 of the small still 3, 4, or 5 gallons, at the cock of the small
 still & the process goes on the same same, as if no beer had
 got in the small still, after the small still is run off
 it would then be proper to take off the cap of the small
 still and clean it.

Chemical Double still. The superiority of

the chemical double still over all others, is, that it saves fuel & labour. It produces more liquor from the same quantity of grain, than any other mode of distilling yet known. By all the modes of distilling, now known, the steam, or vapour is conducted, thro' a pipe, or operates otherwise in a body, or current upon the doubling, in consequence of which the doubling is thrown apart by a single volley of steam which carries with it, watery particles & weakens the spirits.

The Proprietor claims the invention of placing the double still, immediately over the singling still ~~as~~ of the separating the vapour in such a manner as to prevent the liquor that is to be distilled from being thrown apart or from boiling in large volleys; by this invention the watery parts are prevented from getting over with the spirits, unless the large or singling still is overheated; if the fire be kept regular the small still boils imperceptibly & the evaporation of the spirits goes on & leaves the watery particles behind until the volatile part of the spirits is gone over.
